UNITED STATES PATENT OFFICE.

HENRY J. BEHRENS, OF NEW YORK, N. Y.

EARTH-CLOSET.

SPECIFICATION forming part of Letters Patent No. 258,006, dated May 16, 1882.

Application filed February 8, 1882. (No model.)

To all whom it may concern:

Be it known that I, HENRY J. BEHRENS, of New York city, (Tremont,) in the county of New York and State of New York, have invented a new and Improved Earth-Closet, of which the following is a full, clear, and exact description.

The invention consists in a novel construction and arrangement of parts, as hereinafter described, and pointed out in the claims.

Reference is to be had to the accompanying drawings, forming part of this specification, in which similar letters of reference indicate corresponding parts in all the figures.

Figure 1 is a cross-sectional elevation of my improved earth-closet. Fig. 2 is a rear elevation of the same, showing parts broken out. Fig. 3 is a detail cross-sectional elevation of the fixed and swinging hoppers.

20 The privy-seat A is attached to the wall A' of the closet in the usual manner. Above this seat a receptacle or hopper, B, is attached to the outer surface of the wall A', which hopper contains in its upper part a sliding sieve, C, provided with a handle, C', for reciprocating it. The top of the hopper B can be closed by a swinging or sliding gate, D.

25 The lower opening of the hopper consists of a longitudinal slot, E, which can be closed by a valve strip or slat, F, fastened in the ends of and extending longitudinally across the top of a hopper, G, which is pivoted to the bottom of the hopper B, at the rear end of the seat A, in such a manner that this pivoted hopper G can be swung in the direction of the arrow a' by means of a rod, H, attached to the hopper G and projecting from the front or top of the seat; or the hopper G can be provided with any other suitable device for swinging or moving it. The strip or slat F must be of such thickness that it fits closely in the slot in the bottom of the hopper B.

30 The front side, G', of the hopper G hangs down vertically, and the rear side, G², is inclined toward the same; but I do not limit myself to this construction, as the shape and construction of this hopper are not essential and can be varied as may be necessary.

35 The rear side, G², of the hopper must project above the lower end of the hopper B, so that when the hopper G is swung toward the

front the earth or ashes in the hopper B will not drop outside of the hopper-edge of the rear side, G², of the hopper G.

The hopper G is provided with a weight or 55 spring, J, to keep it in a vertical position.

An inclined brace-bar, K, extends from the rear of the seat A to the bottom of the same, and forms a check-bar to prevent swinging the hopper G too far in the direction of the arrow a'. 60

A check-block, T, is attached to the hopper G, and this check-block is adapted to strike against a projecting strip or rail, T', whereby the hopper is prevented from swinging in the inverse direction of the arrow a' beyond the vertical position of the hopper.

55 A box, L, preferably mounted on wheels can be passed under the seat, if the rear gate, M, of the closet is opened; or the closet can be 70 provided with the usual pit.

A ventilating-flue, N, extends from under the seat up to and above the roof of the closet. A wire frame, O, or a series of rods, projects from the top of the strip or slat F.

75 Two U-shaped wires or frames, P and Q, are pivoted at the ends to the top of the slat or strip F, and to the upper ends of these wires or frames P and Q wires R and S are pivoted, the other ends of these wires R and S being 80 pivoted to the opposite sides of the hopper B, so that the wires R and S will be crossed, as is shown in Fig. 3.

In place of the hopper G, a chute or a swinging plate can be used for conducting the ashes 85 or earth from the bottom of the receptacle B upon the excrements; but I prefer a hopper, as shown, as it avoids spreading of dust.

The operation is as follows: Ashes are placed in the sieve C, which is reciprocated so that the 90 sifted ashes will drop into the hopper B, which is closed at the bottom by the slat or strip F. In place of ashes, the hopper B can be filled with sand, earth, sawdust, and similar pulverized material. If the rod H is drawn in the 95 direction of the arrow b', the hopper G will be swung in the direction of the arrow a', whereby the slat or strip F will be swung downward on a curved line, thus opening the bottom of the hopper B and permitting a quantity of the 100 ashes, earth, &c., to drop through the slot E into the hopper G. By swinging the hopper

in the direction of the arrow a' the lower end of the same will be brought under the opening in the seat and the ashes or sand will slide down the rear side, G^2 , of the hopper G upon 5 the feces or excrements in the box L or in the pit, and will cover the same. As soon as the rod H is released the weight J draws the hopper G back into its original position, and the strip or slat F will be moved back into the slot E , 10 which is thus closed, whereby the passage of the powdered material from the hopper B into the hopper G is interrupted. When the box L is filled it is removed and emptied, or the pit provided in place of the box is emptied at proper 15 intervals. All the liquids are absorbed by the ashes, sand, or earth, and the manure in the box or pit will consist of a dry mass, which can be shoveled out of the box or pit very easily. The ventilating-flue N carries off all the ob- 20 noxious and poisonous gases from the box L , so that there will be no bad odors in the closet.

The powdered material—such as ashes, earth, &c.—is apt to become packed and clogged in the lower narrower part of the hopper B , and 25 for the purpose of loosening these materials I have provided the frames O , P , and Q . When the slat or strip F moves downward the upper parts of the wire frames P and Q will be moved downward and toward each other, thereby loos- 30 ening the material at the sides of the hopper B , and the wire frame O , or other suitable pro- jections in place of the same on the strip or slat F , loosen the ashes or earth in the middle of the bottom of the hopper B . When the slat 35 or strip F passes back into the slot E the wire frames O , P , and Q will rise with it, and the upper ends of the frames P and Q will be moved from each other against the sides of the hopper B . If the strip or slat F projects a greater dis- 40 tance into the hopper, less powdered material will pass from the hopper B into the hopper G , and it will not pass as rapidly as if the strip or rail F projected but slightly into the bottom of the hopper B .

45 Having thus fully described my invention, what I claim as new, and desire to secure by Letters Patent, is—

1. In an earth-closet, the combination, with the seat and a receptacle for powdered material, of a swinging hopper for conducting the powdered material upon the excrement, provided with a valve for opening and closing the bottom of the said receptacle, substantially as and for the purpose set forth.

55 2. In an earth-closet, the combination, with the receptacle B for powdered material, of the swinging hopper G and the valve slat or rail F in the top of the swinging hopper for closing the bottom of the receptacle B , substantially

as herein shown and described, and for the 60 purpose set forth.

3. In an earth-closet, the combination, with the receptacle B for powdered material, of the swinging hopper G , provided with a valve slat or rail, F , and of the rod H for operating the 65 swinging hopper G , substantially as herein shown and described, and for the purpose set forth.

4. In an earth-closet, the combination, with the receptacle B , of the swinging hopper G , 70 provided with a valve for opening and closing the bottom of the said receptacle, the rod H , and the weight J , substantially as and for the purpose set forth.

5. In an earth-closet, the combination, with 75 the swinging hopper G , of the receptacle B , the sieve C , and means for reciprocating the sieve, substantially as and for the purpose set forth.

6. In an earth-closet, the combination, with 80 the receptacle B , of the swinging hopper G , and devices, substantially herein shown and described, for loosening the powdered mate- 85 rial in the said receptacle, the said devices being operated by the movement of the said hop- per, as set forth.

7. In an earth-closet, the combination, with the receptacle B for powdered material, of the swinging hopper G , the slat F , and of devices attached to the strip or slat F , for loosening the 90 powdered material in the receptacle G , sub- stantially as herein shown and described, and for the purpose set forth.

8. In an earth-closet, the combination, with the receptacle B for powdered material, of the 95 swinging hopper G , the slat F , the frames P and Q , pivoted to the top of the strip or slat F in the hopper G , and of the pivoted wires R S for connecting these frames with the sides of the receptacle B , substantially as herein shown 100 and described, and for the purpose set forth.

9. In an earth-closet, the combination, with the receptacle B for powdered material, the hop- 105 per G , and the slat F , of the swinging frames P and Q and the fixed frames or projection O on the top of the strip or slat F in the hopper G , and of the wires R S , substantially as herein shown and described, and for the purpose set forth.

10. In an earth-closet, the combination, with the receptacle B and the swinging hopper G , of the check-block T , the projecting rail T' , and the check-bar K , substantially as herein shown and described, and for the purpose set forth.
